UNITED STATES PATENT OFFICE.

MORTIMER FRANKEL, WILLIAM AISENSTEIN, AND JOHN ANTHONY OBERMAIER, OF CHICAGO, ILLINOIS, ASSIGNORS TO WILMORT MANUFACTURING COMPANY, OF CHICAGO, ILLINOIS, A CORPORATION OF ILLINOIS.

CRUMB-SWEEPER.

1,371,615.

Specification of Letters Patent. Patented Mar. 15, 1921.

Application filed January 29, 1919. Serial No. 273,925.

To all whom it may concern:

Be it known that we, MORTIMER FRANKEL, WILLIAM AISENSTEIN and JOHN ANTHONY OBERMAIER, citizens of the United States, 5 residing at Chicago, in the county of Cook and State of Illinois, have invented certain new and useful Improvements in Crumb-Sweepers, of which the following is a specification.

10 Our invention relates to crumb sweeper and has for its particular object the provision of a crumb sweeper adapted to gather crumbs and small particles of food from a table cloth covering the top of a 15 table, and without any manner of injury to the table cloth as by causing lint to be removed from the surface of the table cloth, and at no time requiring downward pressure on the crumb sweeper, but merely necessitating the pushing or pulling of same.

Another and further object of the invention is to provide a crumb sweeper having a revoluble brush which can be readily removed without disturbing the brush operating means, as in service particles of food become lodged in the brush making it desirable to occasionally remove the brush, in order to thoroughly clean it, and also if the brush should become worn or damaged, it 30 is possible to readily renew it, because of the ease with which it can be removed, and a new brush inserted in its place.

Another and further object of the invention is to provide a device which is simple 35 in construction in addition to efficient in operation, and by virtue of this simplicity of construction and exceedingly few parts to secure a device which will maintain in efficient operation for a long time, and which 40 permits of being readily and thoroughly cleaned, which is of importance with regard to a device that is used about a table.

These and other objects of the invention will be further and better understood by 45 reference to the accompanying drawings and in which—

Figure 1 is a view in elevation of the general plan of our invention with the cover removed;

50 Fig. 2 is a vertical sectional view through the sweeper on line 2—2 of Fig. 1; and

Fig. 3 is a sectional view on line 3—3 of Fig. 1.

Referring now specifically to the draw-

ings and in which like reference characters 55 indicate like parts throughout, 10 is a frame member consisting of a single casting in the form of an open topped pan having one pair of double end walls at each end respectively, 11, 12 and 13, 14, and a projection 15 on one side to which an operating handle 16 is secured in any suitable manner, the end walls and projection 15 being integral with said frame member 10. The inner and outer end walls, at each end of the 65 pan define a gear compartment which is open throughout its top. Extending transversely of the pan 10 between the inner end walls 12, 13 is an opening 12^a within which a rotary spiral brush 30 (hereinafter described) is mounted. Mounted in the gear compartments defined by each pair of end walls of the member 10 are two traction wheels 17, 18 and 19, 20 respectively, each of said wheels being mounted upon members 21, 21 which extend through the outer end walls 11, 14, of the frame 10, the members 21, 21 having threaded ends which extend into threaded engagement with the inner end walls 12 and 13 respectively, the 70 members 21, 21 thus serving as axles upon which the traction wheels rotate. Each of the wheels 17, 18, 19 and 20 comprises a gear portion 22 and a flat or hub portion 23 around which a tread member of rubber or 75 other suitable material is fitted, in order to secure the necessary traction, and in order that any surface upon which the crumb sweeper may be placed will not be marred. Mounted upon axles 31 and 32 respectively 80 are gear wheels 25 and 26, each of said gear wheels being in mesh with the gear portion of the traction wheels adjacent thereto. Each of the gear wheels 25, 26 is composed of hub portions 27 and 28, within which the 85 axle 29 of the spiral brush is mounted, the portions 27 and 28 of the wheels 25 and 26 extending through the inner end walls 12 and 13 respectively of the frame member 10. The inner end walls 12 and 13 are provided 90 with upright slots 12' and 13' respectively opening through the tops of said end walls, and the hubs 27 and 28 are accommodated in these slots. Through the outer end walls 11 and 14 extend a pair of threaded members 95 31 and 32, the inside ends of which are reduced in diameter so as to serve as axles for the gear wheels 25 and 26, when assembled 100

as above described with the spiral brush 30. Inwardly extending integrally reinforcing projections 33, 34 are formed upon the inside of the outer end walls 11 and 14 in order to strengthen the mounting for the threaded members, 31, 32, which are held in threaded engagement with the outer end walls 11 and 14 in the projections 33 and 34.

Extending along the marginal edges of 10 the transverse opening 12^a within which the spiral brush 30 is mounted is a pair of vertically extending ribs 35, 36, integral with said frame member 10, and with a pair of vertical extending reinforcing ribs 35^a and 35^b

15 at each of their ends, the said ribs being formed integrally with the inner end walls 12 and 13 and the upright members 35, 36, and serve to strengthen the inside end walls 12 and 13. The object of the ribs 35, 36 of 20 the member 10 is to form a pair of transversely extending troughs or pockets 37 and 38 on each side of the rotating spiral brush 30 within which the crumbs and particles of food are lodged by the rotation of the brush. These members may be merely 25 flanges as shown or may be made as high as desired. The outside lower surfaces of the troughs or pockets 37 and 38 are so shaped that the outside edges form with the upright

30 members 35 and 36, the nearest portions of the frame member 10 to the surface over which the crumb sweeper may be manipulated, all other portions of the frame member 10 being farther away from the surface over which the crumb sweeper may be 35 actuated than these two edges. This means that no portion of the bottom of the frame member 10 is flat or presents a parallel surface to the surface over which the crumb

40 sweeper may be actuated and from inspection of Fig. 2 this may be readily seen, the object being to allow the frame member 10 to readily pass over crumbs, etc., so they can then be picked up by the spiral brush.

45 A removable top or cover member 39 is provided which covers the top of the member 10, fitting in between the outer end walls 11, 14 and is held in position by frictional engagement with the surfaces 40 and 41 of the 50 member 10, the cover being curved and having a slight spring action so as to be held securely in position. The member 10 is provided with thumb depressions so as to make it more convenient to remove the cover 55 member 39 so as to provide means for emptying crumbs out of the crumb sweeper.

The method of operation of the device is very simple, the sweeper being placed upon the surface of the table cloth and then 60 moved back and forth, the hand of the operator grasping the handle 16. The wheels being thus revolved will transmit their motion through the set of gear wheels to the spiral brush 30, which, as the sweeper is moved 65 back and forth, rotates, its direction of rota-

tion changing with the change in the direction of the movement of the sweeper, and the brush in rotating sweeps crumbs and particles of food and lodges them within the transversely extending troughs or pockets 70 37 and 38 formed in the member 10. By backing off the screw threaded axles 31 and 32 until they clear the sockets in the brush gears 25 and 26, the brush 30 with the gears 25 and 26 thereon may be lifted and removed 75 from the pan without disturbing the supporting wheels 17, 18, 19 and 20 and the gears carried thereby. It will now be understood that the open topped slots 12' and 13' accommodate hubs 27 and 28 when inserting and removing the brush. The removability of the brush is an important feature of the present invention, as it frequently becomes necessary to remove the brush for 80 cleaning the same, and the removal may be accomplished without in any manner disturbing the brush operating means, inasmuch as the brush gears 25 and 26 readily go into and come out of mesh with the driving gears without requiring any removal or 85 displacement of the latter.

It will be noted that the traction part of the wheels extends to a slightly lower level than that reached by the brush. This is for the reason that it is common to use a pad 95 under the table cloth or covering for the table so that a slight allowance is necessary to allow the wheels to sink into the cover, thus allowing the ends of the bristles or spiral brush to come in contact with the top 100 of the table cloth to be cleaned.

While we have described more or less precisely the details of construction, we do not wish to be understood as limiting ourselves thereto, as we contemplate changes in form 105 and the proportion of parts and the substitution of equivalents as circumstances may suggest or render expedient without departing from the spirit or scope of our invention.

110 We claim:

1. A crumb sweeper comprising an open topped pan having inner end walls, respective inner and outer end walls defining gear compartments which are open at their tops, the bottom of the pan being provided with a brush-opening extending between the inner end walls, each inner end wall having a vertical slot intersecting the top of the wall, a rotary brush within the pan and extending downwardly through the brush-opening, gears on the ends of the brush, each gear being within one of the gear compartments and having a hub working in the slot in the adjacent inner end wall, the brush with its gears thereon being insertable and removable through the open top of the pan, the slots in the inner end walls permitting the insertion and removal of the brush gears, a pair of supporting wheels in 130

each gear compartment, each wheel extending downwardly through an opening in the bottom of the compartment and having a gear in mesh with the adjacent brush gear,
5 endwise removable brush axles extending through the outer end walls and having their inner ends rotatably supporting the brush gears, and a removable cover closing the top of the pan and the gear compartments.
10 2. A crumb sweeper comprising a single casting in the form of an open topped pan having front, back and outer and inner end walls rising from the bottom of the pan, the respective inner and outer end walls defining gear compartments which are open at their tops, the bottom of the pan being provided with a brush-opening extending between the inner end walls, integral ribs
15 20 extending along the edges of the brush opening, the ribs and the respective front and back walls of the pan defining troughs, each inner end wall having a central vertical slot intersecting the top edge thereof, the bottom 25 of each gear compartment having openings, each outer end wall having an interiorly threaded boss on its inner face and in alignment with the slot in the adjacent inner end wall, a rotatable brush within the pan and

extending downwardly through the brush opening, gears upon the ends of the brush and in the respective gear compartments, each gear having a hub working in the slot in the adjacent inner end wall, the brush with its gears thereon being bodily insertible and removable through the open top of the pan, removable brush axles having threaded engagement with the threaded bosses and rotatably supporting the brush gears, each axle being accessible at the exterior of the pan to permit insertion and removal of the axle, supporting wheels within the gear compartments and extending downwardly through the openings in the bottoms thereof, each wheel having a gear in mesh with the adjacent brush gear, the brush with its gears thereon being insertible and removable while the supporting wheels and their gears are in place, and a removable cover closing the top of the pan and the tops of the gear compartments.
40

Signed at Chicago in the county of Cook and State of Illinois, this 25th day of January, A. D. 1919.
